CLAIM

The ornamental design for a clasp lock, as shown and described.

DESCRIPTION

FIG. 1 is a front, right, and top perspective view of the first embodiment of a clasp lock, showing my new design; FIG. 2 is a rear, left, and bottom perspective view thereof; FIG. 3 is a front elevational view thereof; FIG. 4 is a rear elevational view thereof; FIG. 5 is a left side elevational view thereof; FIG. 6 is a right side elevational view thereof; FIG. 7 is a top plan view thereof; FIG. 8 is a bottom plan view thereof; FIG. 9 is a front, right, and top perspective view of the second embodiment of a clasp lock; FIG. 10 is a rear, left, and bottom perspective view thereof; FIG. 11 is a front elevational view thereof; FIG. 12 is a rear elevational view thereof; FIG. 13 is a left side elevational view thereof; FIG. 14 is a right side elevational view thereof; FIG. 15 is a top plan view thereof; and, FIG. 16 is a bottom plan view thereof.

The broken lines in the drawings depict portions of the clasp lock that form no part of the claimed design.

1 Claim, 16 Drawing Sheets
